UNITED STATES PATENT OFFICE.

JOHN F. O'CONNOR, OF CHICAGO, ILLINOIS, ASSIGNOR TO WILLIAM H. MINER, OF CHAZY,
NEW YORK.

DRAFT-RIGGING.

1,300,460.

Specification of Letters Patent. Patented Apr. 15, 1919.

Application filed December 6, 1916. Serial No. 135,303.

To all whom it may concern:

Be it known that I, JOHN F. O'CONNOR, a citizen of the United States, residing at Chicago, in the county of Cook and State of Illinois, have invented a certain new and useful Improvement in Draft-Rigging, of which the following is a full, clear, concise, and exact description, reference being had to the accompanying drawings, forming a part of this specification.

This invention relates to improvements in draft riggings.

One object of the invention is to provide a detachable draw bar and yoke connection wherein is employed a standard shouldered draw bar and the use of a coupler key is eliminated.

Another object of the invention is to provide a draft rigging wherein is employed a draw bar and yoke having a detachable connection, the detachable connection between the draw bar and yoke being so arranged that the parts are held in assembled relation by the stop members of the draft rigging.

In the drawing forming a part of this specification, Figure 1 is a longitudinal vertical section of a draft rigging showing my improvements in connection therewith. Fig. 2 is a horizontal sectional view taken substantially on the line 2—2 of Fig. 1. Fig. 3 is a vertical, transverse sectional view taken substantially on the line 3—3 of Fig. 1. And Figs. 4 and 5 are detail perspective views illustrating one of the connecting blocks and yoke, respectively.

In said drawing, 10—10 denote channel shaped center sills of a car underframe between which extend upper and lower, horizontally arranged channels 11—11 with their flanges extended upwardly and downwardly, respectively. The channels 11—11 are each provided with a rectangular recess 12 to accommodate the followers 13—13 and vertical twin springs 14—14 of a spring gear. The arrangement is such that the followers and springs can be inserted from below and are held in proper position by a removable saddle plate 15. It will be noted that the webs of the channel stop members are located in line with the axis of the springs to thereby increase the efficiency of the stop members in resisting shocks.

The draw bar 16 is of standard type and is provided with upper and lower shoulders 17—17 on the butt thereof. In view of the

arrangement of stop members, a horizontal yoke 18 is employed, the same comprising a rear connecting portion 19, horizontal side arms 20—20, each of the latter being provided at its front end with a rectangular enlargement forming upper and lower rear shoulders 21—21 and a front, vertical face 22. The enlargements are preferably hollow except for a vertical web 23 which is provided for strength. The enlargements on the ends of the yoke arms are spaced apart sufficiently to accommodate the butt of the draw bar therebetween and, in vertical height, are substantially the same as the vertical height of the draw bar butt. To detachably connect the yoke 18 with the draw bar, I have provided a pair of blocks each of which is designated generally by the reference A. As shown, each of said blocks A comprises a horizontally extending plate portion 24, rear, transversely extending shoulder or flange 25 adapted to engage the rear face of the draw bar butt and a pair of said shoulders 21, and a front, transversely extending shoulder or flange 26 adapted to engage one of the shoulders 17 of the draw bar and against the front faces 22 of the enlarged ends of the yoke arms. Where the front shoulder or flange 26 overlaps the ends of the yoke arms, it is extended downwardly, as indicated at 27 at the corners thereof, to thus provide a larger bearing against the yoke ends.

The blocks A are assembled with the yoke and draw bar in the manner shown most clearly in Fig. 1, that is, with one block on the top of the draw bar butt and the other on the bottom thereof, the latter resting on and supported by the lower stop member 11. It will be noted that the vertical distance between the stop members 11—11 is such as to accommodate the draw bar with the blocks A, A thereon without binding, but in such a manner as to prevent accidental disengagement of said blocks A.

The gear is assembled by first connecting the draw bar and yoke by applying the blocks A, A and then inserting these members longitudinally between the stop castings. The gear proper may then be inserted from below and held in place by applying the saddle plate 15.

From the preceding description, it will be seen that I have provided a simple, detachable connection between a standard draw

bar and yoke and one which obviates the use of all keys or rivets.

I claim:

1. In a draft rigging, the combination with a draw bar having a shouldered butt, of a yoke having upper and lower shoulders on the forward ends of the arms thereof, devices for detachably connecting the draw bar and yoke including, shouldered blocks fitting over the top and bottom shoulders of the butt and said shoulders of the yoke arms, and means for retaining said parts in assembled position.
2. In a draft rigging, the combination with a draw bar having a shouldered butt, of a yoke having upper and lower shoulders on the forward ends of the arms thereof, devices for detachably connecting the draw bar and yoke including, shouldered blocks fitting over the top and bottom shoulders of the butt and said shoulders of the yoke arms, and means for retaining said parts in assembled position, said means comprising upper and lower stop members.
3. In a draft rigging, the combination with a draw bar having a shouldered butt, of a yoke, the ends of the arms of said yoke being shouldered in alinement with the shoulders of the draw bar butt, detachable blocks fitting over said shoulders of the yoke arms and the draw bar butt and means for holding said blocks in operative position.
4. In a draft rigging, the combination with draft sills, of upper and lower horizontally extending stop members, a shouldered draw bar, a horizontal yoke slidably between said

stop members, the ends of the arms of said yoke being provided with shoulders located at the sides of the draw bar butt and detachable upper and lower blocks extending between said ends of the yoke arms and over and below the butt of the draw bar, said blocks being confined in operative relation with the draw bar and yoke by and between said stop members. 40

5. In a draft rigging, the combination with draft sills, of upper and lower horizontally extending front stop members, a horizontal yoke slidably mounted therebetween, a draw bar having the butt thereof also slidably mounted between said members, and detachable means connecting the draw bar butt and the free ends of said yoke arms, said means being held in operative position by and between said stop members. 50

6. In a draft rigging, the combination with draft sills, of upper and lower horizontally extending front stop members, a horizontal yoke slidably mounted therebetween, a draw bar having the butt thereof also slidably mounted between said members, and detachable means connecting the draw bar butt and the free ends of said yoke arms, said means being held in operative position by and between said stop members, said means comprising a pair of blocks having shouldered engagement with the draw bar butt and also with the ends of the yoke arms. 60

In witness that I claim the foregoing I have hereunto subscribed my name this 4th day of Dec., 1916.

JOHN F. O'CONNOR.
